CLAIM

The ornamental design for an auxiliary handle for vegetation-cutting device, as shown in the drawings.

DESCRIPTION

The subject matter of the present application is related to U.S. patent application Ser. No. 29/040,283, filed Jun. 14, 1995, and entitled "Vegetation-Cutting Device", assigned to the assignee of the present application;

U.S. patent application Ser. No. 29/040,286, filed Jun. 14, 1995, and entitled "Handle for Vegetation-Cutting Device", assigned to the assignee of the present application; and

U.S. patent application Ser. No. 29/040,284, filed Jun. 14, 1995, and entitled "Guard for Vegetation-Cutting Device", assigned to the assignee of the present application.

FIG. 1 is a right side perspective view of a preferred embodiment of an auxiliary handle for a vegetation-cutting device in accordance with the present invention;

FIG. 2 is a reduced bottom view;

FIG. 3 is a top view;

FIG. 4 is a front view;

FIG. 5 is a rear view;

FIG. 6 is a left side view; and,

FIG. 7 is a right side view.
